C. C. BLACKMORE

CURTAIN CARRIER

Filed March 19, 1923

UNITED STATES PATENT OFFICE.

CHARLES C. BLACKMORE, OF DAYTON, OHIO, ASSIGNOR TO THE DAYTON TOY & SPECIALTY COMPANY, OF DAYTON, OHIO, A CORPORATION OF OHIO.

CURTAIN CARRIER.

Application filed March 19, 1923. Serial No. 625,984.

My invention relates to curtain carriers.

It is the object of my invention to provide a curtain carrier to support curtains on the doors of vehicles and the like. It is my 5 particular object to provide a detachable carrier, consisting of a detachable rod which supports the curtain on the door of the vehicle, and a socket which is not detachable.

It is an additional object to provide a 10 socket which will maintain the rod in a predetermined position, which will not rotate and become loosened in the door, which may be easily applied to the door after the door is built, and a socket which will provide 15 a slightly appearance and ornament for the door itself.

It is a further object of my invention to provide, in one piece, a complete socket consisting of decorative marginal portion for 20 the exterior of the door, a body portion, and portions therein which will prevent the socket itself from being extracted from or rotated in the door.

It is also a further object of my invention 25 to provide a socket which will prevent the rod from being rotated in it.

It is a further object of my invention to 30 provide a socket and rod combination so arranged that the socket may be located at any desired position, while the rod will be maintained adjacent to the outside of the door, to hold the curtains in the customary position, and to hold the curtains taut, without drooping or sagging.

It is an additional object to provide a 35 socket on the inside of the door or on the top of the door, while still maintaining the same advantages of location of the rod.

Referring to the drawings:

Figure 1 is a plan view, with the rod partially in section, of a rod and socket installed on the top of a door.

Fig. 2 is a sectional view of a portion of a 45 door with my improved device applied thereto and shown in full lines.

Figure 3 is an enlarged plan view of the socket top or head.

Figure 4 is a section on the line 4—4 of Figure 5.

Figure 5 is a section on the line 5—5 of Figure 4.

Figure 6 is a section through a door showing a modified form of socket which is adapted to be attached by a screw to end 55 posts of the doors.

Figure 7 is an end elevation of the rod and socket, with the door in section, showing the socket installed on the inside of the door, and the form of rod used in such a type of installation.

Figure 8 is an enlarged view of the curtain rod shank, showing the tapered construction.

Referring in detail to the drawings, and 65 the construction illustrated therein:

1 designates a door supported on a frame composed of an end post 2 and a top bar 3.

Referring to the socket itself, it will be observed that it is composed of a body portion 4, which is tubular, and usually open 70 at both ends, although the lower end may be closed if desired. The interior of this socket is usually composed of a series of faces 5 for engagement with similar faces 6 on the base of the rod. Slightly rounded 75 corner portions 7 are also provided for engaging with the rounded corners 8 of the rod. The interior of the socket tapers so that its largest diameter is at the top as at 9, and its smallest diameter at the bottom, 80 as at 10. This provides a driving fit for 85 firmly engaging the rod in the socket, as the rod itself is thus tapered.

The rod itself has a taper formed thereon by taking a shear of greater amount nearer 90 the bottom of the rod than at the top. By following this method, I am able to use rods of uniform size, and, by utilizing a progressive shear, secure the desired taper. This greatly facilitates quantity manufacture. I am thus able to use a round rod of 95 uniform diameter with a shank which is square in section, preferably having rounded corners, and so arranged that the round top tapers to the square end. The engagement 95 of the square tapered end with a square tapered socket, prevents the turning of the rod in the socket. This results in the firm engagement of the rod with the curtains, without sagging or other disagreeable features.

The round rod is illustrated in the several figures, while its tapering squared shank is shown in Figure 8.

The top of the socket itself is provided 105 with a beveled rim 11, which forms a shoulder 12 for engagement with the door, to limit the inward movement of the socket within the door. This beveled collar also forms a decorative margin for the socket opening.

On the exterior of the socket body, there are a plurality of fins extending laterally therefrom in a series of steps. The fins are designated 13. The upper portion of the fin, where it extends outwardly from the body, forms a shoulder 14, which prevents the withdrawal of the socket from the soft wood of the door frame. This fin projects downwardly, substantially in a vertical plane as at 15, and then tapers inwardly as at 16, where it merges in the socket wall as at 17. At this point a new shoulder 14 is formed on a new fin. These shoulders 14 are a part of a continuous shoulder 18 which encircles the entire exterior of the socket. There are a series of these shoulders 18 which serve to retard any withdrawal of the socket from the door frame.

I am thus enabled to provide a socket having a tapered angular interior with an exterior having a plurality of associated projecting fins and shoulders. The fins prevent rotating movement of the socket as an entity, and prevent withdrawal of the socket through the agency of the shoulders.

In the event that it is desired to attach the socket to the end post, I have provided a lip 19, which has therein an aperture 20 for the reception of a screw 21. The screw passes through the lip into the end post 2. It will be noted that this lip is disposed to one side of the major axis of the socket, so that a screw may be inserted from either side of the lip, and the post may be located on either side of the lip, or the lip may be rotated to receive the post in any position, as may be desired.

Referring to Figure 7, there will be seen the diagonal form of socket which is used when it is desired to have the socket on the inside of the door, and not on the top of the door. The construction of the socket is the same as that heretofore described, save that the plate 11, instead of being at right angles to the major axis of the socket, is located at an acute angle.

The rod itself consists of the tapered shank portion 6 and 8, which is located at an angle of approximately 45 degrees to a vertical portion 22, which parallels the inside of the door. This portion 22 passes into a right-angled portion over the top of the door, as at 23, which in turn is connected to the portion 24, which is projected

either fore or aft, parallel with the door on top thereof. This serves to support the vertical portion 25 of the rod.

With the form of socket used in the top of the door, the rod consists of the tapered shank portion 6 and 8, the horizontally extending portion along the top of the door 24, and the vertical portion 25.

It will be understood that I desire to comprehend within my invention such modifications as may be fairly embraced within it, and as may be found necessary in adapting it to various conditions in the art in the course of the application of the invention.

Having thus fully described my invention, what I claim as new, and desire to secure by Letters Patent, is:

1. In a curtain carrier socket, a socket body, a plurality of spaced transversely extending shoulders encircling the exterior of the body, and a plurality of vertically extending fins, having the fins extending from one shoulder to the next succeeding shoulder, the lower portion of the fins being tapered.

2. In a curtain carrier socket, a socket body, a plurality of spaced transversely extending shoulders encircling the exterior of the body, a plurality of vertically extending fins, having the fins extending from one shoulder to the next succeeding shoulder, the lower portion of the fins being tapered, and a collar adjacent to the mouth of the socket body, to limit the inward movement of the socket into the door.

3. In a curtain carrier socket, a socket body, a plurality of spaced transversely extending shoulders encircling the exterior of the body, and a vertical fin extending from one shoulder to another, whereby the socket body will be prevented from rotating in the door and from being extracted therefrom.

4. In a curtain carrier, a socket body, a plurality of spaced transversely extending shoulders encircling the exterior of the body, and vertically disposed fins extending from one shoulder to another.

5. In a curtain carrier, a socket body, a plurality of spaced shoulders on the exterior of the body, and vertical fins extending from one shoulder to another.

In testimony whereof, I affix my signature.

CHARLES C. BLACKMORE.
